UNITED STATES PATENT OFFICE

128,821

DESIGN FOR AN INSTRUMENT FOR DETERMINING THE LIGHT-FASTNESS OF COLOR

Clarence W. Jameson, Lombard, Ill., assignor to
Atlas-Ometer Co., Chicago, Ill., a corporation
of Illinois

Application May 31, 1941, Serial No. 101,249

Term of patent 14 years

To all whom it may concern:

Be it known that I, Clarence W. Jameson, a citizen of the United States, residing at Lombard, in the county of Du Page and State of Illinois, have invented a new, original, and ornamental Design for an Instrument for Determining the Light-Fastness of Color, of which the following is a specification, reference being had to the accompanying drawing, forming part thereof.

In the drawing, Fig. 1 is a perspective view and Fig. 2 is a top plan view of an instrument for determining the light-fastness of color, showing my new design.

I claim:

The ornamental design for an instrument for determining the light-fastness of color, as shown.

CLARENCE W. JAMESON.
